UNITED STATES PATENT OFFICE.

WILLIAM H. KELLOGG, OF DETROIT, MICHIGAN.

DESIGN FOR A GARMENT-SUPPORT.

SPECIFICATION forming part of Design No. 26,021, dated September 15, 1896.

Application filed June 29, 1896. Serial No. 597,475. Term of patent 3½ years.

To all whom it may concern:

Be it known that I, WILLIAM H. KELLOGG, a citizen of the United States, residing at Detroit, county of Wayne, State of Michigan, 5 have invented a certain new and useful Design for Garment-Supports; and I declare the following to be a full, clear, and exact description of the invention, such as will enable others skilled in the art to which it pertains 10 to make and use the same, reference being had to the accompanying drawings, which form a part of this specification.

This invention relates to a suspension-hook for garments, and especially relates to the 15 hook that is adapted to engage over the top of the belt and to support a skirt therefrom.

In the drawings, Figure 1 shows the hook in perspective, the view being of the reverse side. Fig. 2 is an obverse elevation.

20 The obverse (shown in Fig. 2) shows a plate having a broad upper bearing along the belt-line, dropping from thence in a substantial

oval or triangular form, having a gracefully curved and figured periphery. The reverse shows at the top the same broad extending 25 line, whence the bounding lines drop in two triangles to the hooks *a b*, which are spaced by a distance of about four-fifths of that of the upper boundary line. The obverse and reverse are united by a sharply-curved face 30 that forms the top, and this curved face is also curved in its long direction between the ends *c d*. The obverse presents along the lines which bound its lower sides ornamental raised figures.

35

What I claim is—

The design for a garment-support as shown and described.

In testimony whereof I sign this specification in the presence of two witnesses.

WILLIAM H. KELLOGG.
